WALKIE-TALKIE

Eizo Komata and Hiroharu Shimazaki, Tokyo, Japan,
assignors to Kanda Tsushin Kogyo Kabushiki Kaisha,
Tokyo, Japan, a corporation of Japan

Filed Aug. 8, 1966, Ser. No. 3,375

Term of patent 7 years

(Cl. D26—14)

FIG. 1

FIG. 2

FIG. 3

FIG. 4

FIG. 5

FIG. 6

FIG. 7

FIG. 1 is a front view of the walkie-talkie showing the design of the invention.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom front view thereof.

FIG. 7 is a perspective view thereof seen from the upper right hand side of FIG. 1.

I claim:

The ornamental design for a walkie-talkie, substantially as shown.
